By Att. Milwaukee, W. H.

UNITED STATES PATENT OFFICE.

ADOLPH P. GUSTAFSON, OF CHICAGO, ILLINOIS, ASSIGNOR TO M. SCHULZ COMPANY, OF CHICAGO, ILLINOIS.

SHEET CONTROLLED OR OPERATED MUSICAL INSTRUMENT.

Application filed June 23, 1922. Serial No. 570,428.

My invention relates to sheet controlled or operated musical instruments, such for example, as player pianos and the like.

The principal object of the invention is to improve the arrangement by which the music sheet may be held in proper position for operation, as for example, in proper position relative to a tracker board.

In the accompanying drawings Fig. 1 is a view of a portion of a sheet operated musical instrument having sheet controlling mechanism embodying my present invention;

Fig. 2 is an end elevation of the same.

Fig. 3 is a cross section taken on line 3-3 in Fig. 1;

Figs. 4 and 5 are views of details of construction.

Referring to the drawings, I show a music box 1 in which are mounted the supporting spindles 2 and 3 of the music roll 4. A music sheet 5 is carried by the roll 4 and travels over a tracker 6.

Means are provided for engaging the roll 4 and adjusting the same longitudinally and for holding the same in longitudinal adjustment. The means shown comprise a pneumatic 7 connected by link 8 to arm 9 on rod 10. Rod 10 is provided with cross rods 11-11 which extend to and are connected to rod 12. At the ends of rod 12 are pivoted members 13-13 pivoted by pins 14-14 to said rod 12 near its ends. The rod 12 is preferably provided with a plurality of apertures 15 by which the pivotal connection may be changed. The lugs or pivoted members 13 are provided with discs 16 preferably flat and having axial pins or stems 17 by which they are connected to the members 13. By reason of their weight members 13 normally incline downwardly as shown in Fig. 5.

The pneumatic 7 is shown connected with and in the instrument that it will automatically turn so as to swing the arms 11 downwardly when playing is to be started and will hold them downwardly during such playing. As such apparatus is no part of my present invention, being shown, described and claimed in my application Serial No. 187,942, filed August 24, 1917, for tracking device, my present invention

lying in the rod 10 and associated parts. When the pneumatic is collapsed and rod 10 turned and arms 11 swung downwardly, lugs 13 will move toward spool 4 and wheels or discs 16 will strike against the spool, as shown in dotted lines in Fig. 3. This will swing lugs 13 upwardly so that they will come into substantial alinement with rod 12. The outer edges of discs 16 will engage and act against flanges of roll 4 so as to adjust said roll into proper tracking position, and will retain it there as long as pneumatic 7 is collapsed. As roll 4 rotates the flanges may and do, to a more or less extent, rotate wheels or discs 16, so that friction is practically avoided.

The arrangement is very simple and advantageous in operation and inexpensive to manufacture.

It will be understood that changes and modifications may be made without departing from the spirit of the invention.

What I claim is:

1. The combination with the music box of a pneumatic playing instrument, of the music roll therein and mechanism for controlling the music roll comprising a rotatable rod extending lengthwise of the roll near the same, cross rods extending from said longitudinal rod, a second longitudinal rod at the ends of said cross rods and rotary members carried by said second mentioned longitudinal rod and adapted to engage the flange of the music roll.

2. The combination with the music box of a pneumatic playing instrument, of the music roll therein and mechanism for controlling the music roll comprising a rotatable rod extending lengthwise of the roll near the same, cross rods extending from said longitudinal rod, a second longitudinal rod at the ends of said cross rods and rotary members carried by said second mentioned longitudinal rod and adapted to engage the flange of the music roll, said second longitudinal rod being provided with pivoted end pieces by which said rotary members are carried.

In witness whereof, I hereunto subscribe my name this 15th day of May, A. D., 1922.

ADOLPH P. GUSTAFSON.
